UNITED STATES PATENT OFFICE.

LEWIS E. CURTIS, OF WARREN, OHIO, ASSIGNOR TO THE YOUNGSTOWN PRESSED STEEL COMPANY, A CORPORATION OF OHIO.

EXPANDED-METAL LATH.

Application filed May 31, 1923. Serial No. 642,633.

To all whom it may concern:

Be it known that I, LEWIS E. CURTIS, a citizen of the United States, residing at Warren, in the county of Trumbull and State of Ohio, have invented a new and useful Improvement in Expanded-Metal Lath, of which the following is a specification.

The present invention relates to improvements in expanded metal lath, and will be 10 fully understood from the following description, illustrated by the accompanying drawings, in which:

Figure 1 is a plan view (broken) of a slotted blank prepared for use in producing 15 expanded metal lath in accordance with the present invention;

Fig. 2 is a sectional view on the line 2 of Fig. 1;

Fig. 3 is a plan view (broken) of the 20 blank shown in Fig. 1 after the bonds have been ribbed or grooved;

Fig. 4 is a broken sectional view on the line 4 of Fig. 3;

Fig. 5 is a broken sectional view on the 25 line 5 of Fig. 3;

Fig. 6 is a broken plan view of a portion of the blank in the stage of operation subsequently to that shown in Fig. 3, the longitudinal stay portions being grooved;

Fig. 7 is a broken sectional view on the 30 line 7 of Fig. 6;

Fig. 8 is a broken sectional view on the line 8 of Fig. 6;

Figs. 9 and 10 are enlarged broken 35 sectional views on an enlarged scale corresponding to Figs. 7 and 8;

Fig. 11 is a broken plan view on an enlarged scale of a portion of the blank in the stage of operation shown in Fig. 6;

Fig. 12 is a broken plan view of a portion 40 of the lath after expansion;

Fig. 13 is a section on the broken line 13-13 of Fig. 12, and

Fig. 14 is a broken sectional view on the 45 line 14 of Fig. 12.

In producing an expanded lath in accordance with the present invention, a blank is first formed from relatively thin sheet metal by forming at spaced intervals longitudinal series of transverse rows of alternately overlapping inclined slits or cuts 50. The slits cut in this manner leaves between them bond portions 11. The transverse spacing of the rows of the slots leaves, 55 longitudinal solid or stay portions of the

blank indicated by the numeral 12, which, in the subsequent evolution of the lath, become longitudinal reinforcing members or ribs. It will further be noted from a study of Fig. 1 that the angular inclinations of the 60 slits cut on each side of the intermediate longitudinal stay portions 12 are opposite; for example, the slits in the portion indicated by the bracket *a* in Fig. 1 are inclined opposite those in the portion indicated by 65 the bracket *b*.

The blank, slotted in the manner just described, is then subjected to grooving operations in order to groove the bonds 11. The transverse rows of bonds 11 are alternately grooved upwards and downwards. Thus, a row of bonds 11^a may be grooved 70 upwardly, so as to present a convex appearance when viewed from above (see Fig. 4), and the next row of bonds 11^b 75 will be grooved downwardly, so as to present a concave appearance when viewed from above (Fig. 5). The next row of bonds will again be grooved upwardly and the succeeding row downwardly. The 80 grooving operation opens the slits 10 slightly, as shown clearly in Figs. 3, 4 and 5 of the drawings. The appearance of the blank at this stage of evolution is clearly shown in those figures, the sections being on 85 an enlarged scale.

The longitudinal stay or solid portions are then grooved to form ribs, the grooves extending longitudinally of the blank. The blank then assumes the appearance shown 90 in Fig. 6 and in sectional Figs. 7, 8, 9 and 10. Figs. 9 and 10 correspond to Figs. 7 and 8, being, however, on an enlarged scale. From these figures the slight opening of the slits 10 is more clearly apparent. Fig. 11 95 shows a marginal portion of the blank at this stage on an enlarged scale.

The expanding mesh of the fabric is then formed by lateral or transverse stretching or displacing of the portions of the sheet 100 between the longitudinal ribs 12 and 12^a, the numeral 12^a being used to indicate the ribs at the margins of the sheets or blanks. In the opening of the sheets in this manner, the transverse rows of bonds 11^a and 11^b are 105 forced into a position in which they are inclined to the transverse direction across the sheet which they previously occupied, the direction of inclination preferably being opposite on opposite sides of the intermediate 110

stays or solid portions 12. Thus, in Figs. 1, 3 and 6, it will be noted that the rows of bonds 11^a and 11^b extend transversely across the sheet; that is, a line passing through their centers would be substantially perpendicular to the edges of the sheet. In Fig. 7, the section line 8 is drawn through such a row of bonds 11^b, and it will be noted that in the expansion of the sheet, as already stated, this row of bonds has been forced into an inclined position. Every alternate rib or stay moving longitudinally with respect to those on each side of it. In the expanded blank at this state of evolution, the open meshes 13 have the appearance of the meshes of that type of lath commonly designated as "cup lath". It is to be noted, however, that on each side of the intermediate stays or solid longitudinal portions 12, the meshes are inclined diagonally and preferably in opposite directions, and the lines of grooving of the bonds are likewise diagonal and inclined in opposite directions. As a result of this construction, the expanded lath is greatly strengthened there being no lines of weakness extending longitudinally or transversely across the sheet. It is also to be noted that the expansion of the sheet or blank formed in the manner described does not necessitate shortening the longitudinal stays or solid portions, 12, as the sides of the meshes 13^a adjacent the stays 12 that are closed by the latter are longer than the other sides of the mesh. In the opening up of the blank, these meshes 13^a are deformed as compared with the intermediate meshes and, by their deformation, in part take care of such longitudinal contraction as occurs as a result of the expansion of the sheet.

In describing the formation of expanded metal lath in accordance with my invention, I have, for the purpose of illustration, described the operations upon the blanks in a specific sequence. I may, however, carry out these steps in a different order or may carry out certain of them simultaneously by the use of certain apparatus without departing from my invention.

I claim:

1. An expanded metal lath having spaced longitudinal stay portions and intermediate

deflected strands forming meshes having their median lines inclined at an angle to said stay portions and the bonds of said meshes being grooved.

33

2. An expanded metal lath having spaced longitudinal stay portions and intermediate deflected strands forming meshes having their median lines inclined at an angle to said stay portions, the meshes on opposite sides of each intermediate stay portion being angularly inclined in opposite directions and the bonds of said meshes being grooved.

60

3. An expanded metal lath having spaced longitudinal stay portions and intermediate deflected strands therebetween forming meshes, the bonds of said strands being arranged in rows inclined at an angle to said stay portions, and said rows of bonds being alternately grooved in opposite directions whereby a cupped mesh is formed.

65

4. An expanded metal lath having spaced longitudinal grooved ribs and intermediate deflected strands therebetween forming meshes, the bonds of said strands being arranged in rows inclined at an angle to said grooved rib, and said rows of bonds being alternately grooved in opposite direction whereby a cupped mesh is formed.

75

5. The method of forming an expanded metal lath which includes the steps of providing in a sheet metal blank spaced longitudinal series of transverse overlapping rows of inclined slits, the slits of the adjacent longitudinal series being oppositely inclined, oppositely grooving successive transverse rows of bonds between slits in said longitudinal series of slits and extending the blank transversely to open the slits thereby forming open meshes.

80

6. The method of forming an expanded metal lath which includes the step of providing in a sheet metal blank spaced longitudinal series of transverse overlapping rows of inclined slits, oppositely grooving successive transverse rows of bonds between slits in said longitudinal series of slits, grooving the longitudinal portions of the blank between said rows of slits, and extending the blank transversely to open the slits, thereby forming open meshes.

90

LEWIS E. CURTIS.
